CLAIM

The ornamental design for a seal plate, as shown and
described.

DESCRIPTION

FIG. 1 is a front elevational view of a seal plate showing
my new design;FIG. 2 is a right side elevational view thereof; the top,
bottom, and left side elevational views are
identical to the right side elevational view;FIG. 3 is a sectional right side elevational view thereof,
taken along the line 3—3 of FIG. 1; the section lines
form no part of the claimed design;

FIG. 4 is a rear elevational view thereof; and,

FIG. 5 is an enlarged, sectional, fragmented view of the
rim of the seal plate of FIG. 3.FIG. 2
